No Drawing. Application November 24, 1952,
Serial No. 322,356

5 Claims. (Cl. 167—55)

This invention relates to diuretic compositions, and 15 more particularly to a composition containing an agent which serves to increase the elimination of cations, principally sodium and potassium.

The invention also involves the process of increasing the elimination of cations, and more particularly the sodium cation, from the body of man or other animals. This process involves the administration of the active 20 agent and the regulation of the quantity consumed so as to bring about this desired result.

Many persons suffer from an abnormal retention of 25 sodium, principally as the chloride. This may result in the development of edema, may precipitate an episode of congestive heart failure, or may aggravate a pre-existing hypertension. One way to overcome this is to decrease the amount of sodium chloride intake, but this is an unsatisfactory solution for the reason that many such foods are unpalatable. That is, people object so much to the bland taste of the food that they refuse to adhere to a regime of an extremely low salt consumption.

In accordance with the present invention a composition is provided which, when consumed, makes it possible for 30 a person to apply the desired amounts of salt to his food. The composition of the invention serves to provide for excretion of a major amount of this salt intake with the result that the patient is allowed a diet to which he will 35 adhere and at the same time the daily salt balance approximates that resulting from moderate to severe salt restriction without the aid of this invention.

Furthermore, there are a number of clinical indications 40 for the use of the composition of the invention. In various edematous states it is desirable to eliminate cations, and principally the sodium cations, from the body, in order to bring about a reduction of the edematous condition. By giving such a patient the composition of the 45 invention, this condition will be markedly improved.

The value of salt restriction as a means of limiting the 50 development of edema is well documented. The composition of the invention may be particularly useful in the patient prone to congestive heart failure.

The active agent of the composition of the invention 55 is para-carboxybenzenesulfonamide (or para-sulfamylbenzoic acid), having the structural formula:

This active agent may be combined with either a solid 60 or a liquid carrier or diluent. The resulting compound may be put up in the form of tablets, powder, or capsules, or in any form which can be used for oral consumption. Likewise, the liquid preparation may be bottled or even put up in encapsulated form for ease of oral administration. The liquid form may as well be for parenteral administration and in this event precautions should of course be taken to produce a sterile composition.

In making the composition, conventional pharmaceutical practices may be carried out and this applies to com-

2

positions for either oral or parenteral use. Ordinary care should be exercised to make sure that no incompatible condition exists with respect to the diluent which is being employed. In the liquid preparation, the active ingredient may be either in complete solution or may be in suspension.

Irrespective of the particular kind of dosage form which is made, the unit dosage of the composition should contain therapeutic amounts of the active agent. Thus, a unit dosage of the ingredient will contain from 10 mg. to 16 gm., a more preferred range being from 100 mg. to 4.0 gm. The total daily oral intake for an adult should be from 0.5 to 16 grams, and most generally from 2 to 8 grams. About one-fourth these amounts would be taken parenterally. Bearing in mind that a person required to take this composition will ordinarily prefer at one time to take one or a few tablets or capsules, or one or a few tablespoons of a liquid preparation, or a few cc. of an injectable preparation, the frequency of administration is apparent.

As a further feature of the invention, compositions are provided which are free of any material amounts of sodium or potassium. As a primary purpose of the invention is to increase the elimination of these cations, it follows that it would be desirable not to introduce any sodium or potassium into the person with the active agent of the invention. As ordinary pharmaceutical compositions contain sodium and potassium compounds, a feature of the invention resides in their elimination (other than as slight contaminants) from the compositions of the invention.

Representative compositions, in accordance with the invention, are the following, and from them other suitable compositions will be apparent.

Example I.—Compressed tablets

p-Carboxybenzenesulfonamide	57 lb. 13 oz.
Dextrose white NF V	4 lb. 8 oz.
Corn starch paste, 1 part	1 lb. 8 oz.
Gelatin solution, 2 parts	
Distilled water, q. s.	
Starch USP dried—MF 3000	7 lb. 8 oz.
Talc USP	3 lb. 8 oz.
Magnesium stearate purif. imp. powd.	3 oz.

Total weight granulation 75 lb.

Compress into 0.65 gram tablets each containing 0.5 gram of p-carboxybenzenesulfonamide. Theoretical yield: 52,500.

Example II.—Sterile solution

	Grams
Ammonia water 28.3% NH ₃	19.54
p-Carboxybenzenesulfonamide	50
Pyrogen-free double distilled water, q. s.	

Theoretical yield: 500 cc.

Sterilize in bulk by autoclaving at 121° C. (250° F.) for 2 hours.

Fill into sterile 10 cc. ampuls, filling 10.5 cc. per ampul each containing 1.0 gram of p-carboxybenzenesulfonamide.

Example III.—Dry filled capsules

	Kg.
p-Carboxybenzenesulfonamide	4
Corn starch USP	0.8

4.8

Yield: 8000 capsules each containing 0.5 gram of p-carboxybenzenesulfonamide.

Example IV.—Soft elastic capsules

p-Carboxybenzenesulfonamide ----- kilo 5
Peanut oil, q. s. (to form soft creamy mixture).

Make into soft elastic capsules of a suitable size, each capsule representing 500 mg. p-carboxybenzenesulfonamide.

Example V.—Suspension (oral)

	Percent
p-Carboxybenzenesulfonamide	10
Kaolin	10
Pectin	1.0
Sugar, USP granulated	10
Glycerin	10
F. D. & C. orange #1	0.005
Oil sweet orange, sesquiterpeneless	0.02
Benzoic acid	0.2
Alcohol	5.0
Distilled water, q. s. ad.	

Each 10 cc. of the suspension mixture contains 1.0 gram of the p-carboxybenzenesulfonamide.

Example VI.—Effervescent granule

p-Carboxybenzenesulfonamide	kg	4
Dulcin	kg	0.025
Calcium carbonate powder USP	kg	3.375
Corn starch paste 12.5% 1000 cc. allow	kg	0.100
Distilled water, a sufficient quantity about 250 cc.		
Citric acid fine USP granules	kg	0.5
		8.0

Yield: 2000 doses.

Each 4 gm. of granular material contains 2 gm. of p-carboxybenzenesulfonamide.

Example VII.—Granule

p-Carboxybenzenesulfonamide	kg	4
Powdered sugar USP	kg	1.5
Corn starch USP	kg	0.5
Distilled water, a sufficient quantity, about 1000 cc.		6

Yield: 2000 doses.

Each 3 gm. dose of granular material contains 2 gm. of p-carboxybenzenesulfonamide.

Example VIII.—Effervescent tablet

p-Carboxybenzenesulfonamide	kg	4
Dulcin	kg	0.025
Calcium Carbonate USP powder	kg	3.325
Corn starch paste 12.5% 1.5 liters allow	kg	0.150
Distilled water, a sufficient quantity, about 0.5 liter.		50
Citric acid USP fine granules	kg	0.47
Magnesium stearate	kg	0.03
		8.0

Theoretical yield: 2000 tablets, each weighing 4 grams and each containing 2 grams of p-carboxybenzenesulfonamide.

Example IX.—Effervescent powder

p-Carboxybenzenesulfonamide	Kg.	60
Dulcin		0.025
Calcium carbonate USP powder		3.475
Citric acid USP powder		0.5
		8.0

Yield: 2000 doses of 4 grams each, each containing 2 grams of p-carboxybenzenesulfonamide.

Example X.—Powder

p-Carboxybenzenesulfonamide	Kg.	70
Powdered sugar USP		2

Yield: 2000 doses, each weighing 3 grams and each containing 2 grams of p-carboxybenzenesulfonamide.

Other examples of the composition of the invention having the p-carboxybenzenesulfonamide present in smaller or greater concentration will be apparent. Thus the active agent could be present in as low as 1 or 2% by weight of the composition, especially if a clear aqueous solution of relatively insoluble derivatives (hereinafter mentioned) of the p-carboxybenzenesulfonamide are to be used. However, because of the relatively large amount of the active agent which must be taken daily, the higher relative proportions, as 10% and more, are to be recommended and this may be even 100% if the patient can tolerate the undiluted p-carboxybenzenesulfonamide. The active material in this latter case can be packaged as the pure compound and be labeled for medicinal use with instructions by the physician as to the quantity and frequency of consumption by the patient.

As has been mentioned, a daily amount of from 2 to 16 grams may be prescribed. In most instances the daily intake will be from 4 to 8 grams. The attending physician can determine the proper daily consumption by physical observation of the patient and by measurement of the patient's sodium and potassium balance. Based on this information, the daily administration should be regulated to approximately the minimum to bring about and maintain the desired sodium and potassium elimination.

Although the invention has been described with particular reference to p-carboxybenzenesulfonamide, numerous derivatives of it may be employed as they presumably yield this acid in the body. For example, as is evident from Example II, the ammonium salt may be utilized. The sodium or potassium salt may be used, but as has been mentioned, this is counterindicated as it introduces the ions which are intended to be eliminated from the body. Other salts may be utilized by replacing the hydrogen of the carboxyl group.

The invention contemplates as well other derivatives of the acid, and this includes the lower alkyl esters, the amide, and either the mono or the disubstituted lower alkyl derivatives of the amide form. Representative compounds which may be substituted in the above examples in amounts to yield an equivalent therapeutic effect, are the following:

Ethyl p-sulfamylbenzoate

p-Sulfamylbenzamide

p-Sulfamyl-N-methylbenzamide

p-Sulfamyl-N,N-dimethylbenzamide

p-Sulfamyl-N,N-di-n-propylbenzamide

n-Butyl p-sulfamylbenzoate

p-Sulfamyl-N-n-propylbenzamide

Isopropyl p-sulfamylbenzoate

sec-Butyl p-sulfamylbenzoate

These compounds are commercially available or may be made by processes common in the chemical art.

What is claimed is:

1. The process of increasing the elimination of an ion selected from the group consisting of sodium and potas-

sium ions from the body which consists in administering to a living person suffering from an abnormal retention of these ions p-carboxybenzenesulfonamide in an amount sufficient to eliminate the excess sodium and potassium ions and bring about the desired electrolyte balance in the person.

2. The process of increasing the elimination of an ion selected from the group consisting of sodium and potassium ions from the body which consists in orally administering to a living person suffering from an abnormal retention of these ions p-carboxybenzenesulfonamide in an amount sufficient to eliminate the excess sodium and potassium ions and bring about the desired electrolyte balance in the person.

3. The process of increasing the elimination of an ion selected from the group consisting of sodium and potassium ions from the body which consists in parenterally administering to a living person suffering from an abnormal retention of these ions p-carboxybenzenesulfonamide in an amount sufficient to eliminate the excess sodium and potassium ions and bring about the desired electrolyte balance in the person.

4. The process of increasing the elimination of an ion selected from the group consisting of sodium and potassium ions from the body which consists in administering to a living person suffering from an abnormal retention of these ions from $\frac{1}{2}$ to 16 grams daily of p-carboxybenzenesulfonamide in an amount sufficient to eliminate the excess sodium and potassium ions and bring about the desired electrolyte balance in the person.

5. A method of increasing the elimination of an ion selected from the group consisting of sodium and potassium ions from the body which comprises administering a composition comprising not less than 1.0% by weight of p-carboxybenzenesulfonamide to a person suffering from an abnormal retention of these ions.
